COMBINED REFLECTOR AND SOCKET FOR ELECTRIC LAMPS

Jacob A. Mehr, Kirkwood, Mo., assignor to Dazor Manufacturing Corp., St. Louis, Mo., a corporation of Delaware

Application September 16, 1955, Serial No. 37,959

Term of patent 14 years

(Cl. D48—16)

FIG. 1.

FIG. 2.

FIG. 3.

FIG. 4.

FIG. 5.

Fig. 1 is a top plan view of a combined reflector and socket for electric lamps;

Fig. 2 is a bottom plan view thereof;

Fig. 3 is a vertical sectional view taken at line 3—3 of FIG. 2;

Fig. 4 is a rear elevational view thereof, and

Fig. 5 is a side elevational view thereof.

I claim:

The ornamental design for a combined reflector and socket for electric lamps, substantially as shown.
